C. F. GILCHRIST.
STARTING SWITCH.
FILED Nov. 30, 1917.

FIG. V. Inventor

C. F. Gilchrist

384 Chester H. Braselton
Attorney

UNITED STATES PATENT OFFICE.

CLARENCE F. GILCHRIST, OF TOLEDO, OHIO.

STARTING SWITCH.

Application filed November 30, 1917. Serial No. 204,628.

To all whom it may concern:

Be it known that I, CLARENCE F. GILCHRIST, a citizen of the United States, residing at Toledo, in the county of Lucas 5 and State of Ohio, have invented certain new and useful Improvements in Starting Switches, of which I declare the following to be a full, clear, and exact description.

This invention relates to electric switches, 10 particularly of that class employed in the electrical circuit of a starting motor for internal combustion engines.

The object of this invention is to provide a switch of the above named class, which 15 will have a very low resistance to the passage of electricity, and at the same time be of compact form. A further object is to devise a switch with an intermediary contact which will automatically adjust itself to the 20 various parts. Another object is to provide a switch of the type above indicated, which will vary its resistance in proportion to the degree of compression of the actuating means.

25 Further objects, and objects relating to economies of manufacture and details of construction, will definitely appear from the detailed description to follow:

I accomplish the objects of my invention 30 by the devices described in the following specification. My invention is clearly defined and pointed out in the appended claims.

A structure constituting a preferred embodiment of my invention is illustrated in 35 the accompanying drawings, forming a part of this specification, in which:

Figure I is a view, in side elevation, of the switch connected in circuit with a starting motor and a battery;

40 Figure II is a vertical section taken on line II—II of Figure III;

Figure III is a horizontal section, taken on line III—III of Figure II;

45 Figure IV is a detail section view, through the contact ring, taken on line IV—IV of Figure II, and,

Figure V is a section taken on line V—V of Figure II.

In the drawings, similar reference numerals refer to similar parts throughout the 50 several views, and the sectional views are taken looking in the direction of the little arrows at the ends of the section lines.

As illustrated, the switch comprises in 55 brief, a supporting plate 1, an operating

button 2, a connecting rod 3, a contact ring 4, terminal contacts 5 and 6, and casing 7. The supporting plate 1 has apertures 8 to receive bolts or screws for attaching the switch to the vehicle. Centrally disposed in 60 the plate is a raised cylindrical bearing 9, apertured as at 10, to receive the actuating rod 3. The diameter of the aperture 10 is increased at 11, to receive an absorbent packing 12, designed to receive oil to lubricate 65 the actuating shaft and to keep out dust from the switch interior. The shaft 3 is a cylindrical metal rod, slideable in the bearing 9 and has attached at its upper terminal, by means of a pin 13, an operating button 70 2, and towards its lower end, the contact ring 4. The button consists of a metal unit having a bead 14, a body 15, and a hollow cap 16, designed to fit over the support bearing 9 and serving as a guide to the downward movement of the connecting rod 3. The base 17, of the cap 16, serves as an abutment to limit the downward movement of the rod.

Towards the lower end of the connecting 80 rod 3, the contact ring 4 is applied. This ring is made of a circular band of copper, and fits loosely over an insulating bushing 18. An insulating washer 19, holds the ring from axial movement on the bushing and 85 the whole is held together and in place on the rod by means of metallic washers 20 and 21. Bearing on the lower washer 21, at the base of the ring bushing 18, and encircling the rod 3, is the upper terminal of a 90 spiral band spring 22. The lower end of this spring terminates adjacent the end of the rod 3, and has a bearing on the base 23, of the cylindrical casing 7, which is attached to the supporting plate 1, by screws 24. 95

The contact terminals 5 and 6 are identical in construction, and consist of resilient bands of metal, bent into semi-circular form, from one side of which extend converging strip fingers 25, with out-turned terminals 26. 100 These contacts are placed inside the casing with the semi-circular bands 27, in juxtaposition, but not in contact, thus forming, in effect, a hollowed inverted truncated cone with resilient sides. These separated contacts 5 and 6 are fastened at diametrically opposite points to the casing 7, at points where they are normally out of engagement with the ring 4, but such that, on downward movement, the ring will contact firmly there- 110

- with. The contacts are secured in place by means of bolts 28, which with the contacts are insulated from the casing 7, by a circular insulating ring 29. The bolts are further insulated from the casing by the insulator rings 30 and 31. The bolts and insulators are held firmly in place by the metallic washers 32, and nuts 33, the nuts in addition binding the circuit terminals 34 in place.
- 10 In the casing base 23, the operating rod 3 is movable through an aperture 35, which centers the rod and serves as a bearing therefor.

15 The operation of the switch will now be described. When the button 2 is depressed against the resistance of the spiral spring 22, the ring 4 moves downwardly, until it contacts with the resilient fingers, thereby completing the electrical circuit. If the rod 20 3 is off center, relative to the spring fingers 25 and 26, the ring, since it is movable laterally, is shifted until it bears with equal pressure on the opposing spring contact fingers. Further compression of the ring 4 25 forces the fingers outwardly, the changing curvature of the same allowing of greater contact area between the contacting parts, until the limit of movement is reached where the compression of the fingers and 30 area of contact is greatest, and therefore the resistance is least. It is evident that the sliding action of the ring on the contact fingers tends to keep them clean and smooth, and thus increase the electrical conductance 35 at the points of contact.

I am aware that the particular embodiment of my invention, here shown and described, is susceptible of considerable variation without departing from the spirit of 40 my invention, and, therefore, I desire to claim the same broadly, as well as specifically, as indicated by the appended claims.

Having thus described my invention, what I claim as new and desire to secure by Letters Patent, is:

1. In an electric switch, the combination of a casing; a supporting plate; a connecting rod movable transversely through the supporting plate; an actuating button on one 50 end of the connecting rod; a contact ring adjacent the other end of the connecting rod and insulated therefrom, said ring being capable of lateral movement only, relative to the connection rod; terminal inwardly projecting contact fingers attached to the casing and insulated therefrom; and a spiral spring intermediate the contact ring and casing adapted normally to hold the ring and fingers out of contact with each other.
- 60 2. In an electric switch, the combination

of a longitudinally reciprocable actuating rod; a pair of contacts normally insulated from each other and each provided with a plurality of curved contact fingers; and a ring mounted on said rod and insulated 65 therefrom, said ring being adapted to engage said fingers to electrically connect said contacts together, and said ring having a slight lateral movement relative to said rod.

3. In an electric switch, the combination 70 of a longitudinally reciprocable actuating rod; a pair of contacts normally insulated from each other and each provided with a curved contact finger; and a ring mounted on said rod and insulated therefrom, said 75 ring being adapted to engage said fingers to electrically connect the said contacts together, and said ring being constructed to have a limited lateral movement relative to said rod whereby it may engage the two contacts with substantially equal pressure.

4. In an electric push button switch, a cylindrical casing, a pair of curved contact members secured to said casing each having a plurality of inwardly extending fingers, a 85 push rod extending through said casing, a contact ring having a cylindrical outer surface mounted on said push rod to have limited lateral movement thereon, the fingers initially contacting with an edge of the ring 90 and finally contacting with the said cylindrical surface whereby the said ring is self adjusting to bear with substantially equal pressure on both sets of fingers and the final contact resistance is less than the initial contact resistance.

5. In an electric push button switch, a cylindrical, casing, a pair of curved resilient contact members within said casing, a terminal post electrically connected to and securing each of said members to the curved wall of said casing, said posts extending radially from opposite sides of said casing, a push rod extending through said casing, and a contact member carried by said rod to 100 have sliding engagement with said contact members.

6. In an electric push button switch, a pair of oppositely disposed contact members, a push rod mounted for longitudinal 110 movement between said members, a bushing of insulating material secured to said rod, and a contact ring mounted upon said bushing said ring having a slightly larger internal diameter than said bushing permitting it 115 to have limited lateral movement as it contacts with said contact members.

In testimony whereof, I affix my signature.

CLARENCE F. GILCHRIST.
